CLAIM

The ornamental design for golf club grip, as shown and described.

DESCRIPTION

FIG. 1 is a perspective view of the golf club grip showing my new design;

FIG. 2 is a top plan view thereof;

FIG. 3 is a side elevational view thereof, it being understood that the bottom plan view is identical thereto and the opposite side view is a mirror image thereof;

FIG. 4 is an end view of the large end thereof; and,

FIG. 5 is an end view of the small end thereof.
